UNITED STATES PATENT OFFICE.

ALEXANDER J. MACKENZIE, OF BUFFALO, NEW YORK.

CORD-FASTENER.

1,148,847.

Specification of Letters Patent.

Patented Aug. 3, 1915.

Application filed July 14, 1914. Serial No. 850,909.

To all whom it may concern:

Be it known that I, ALEXANDER J. MACKENZIE, a citizen of the United States, residing at Buffalo, in the county of Erie and State of New York, have invented certain new and useful Improvements in Cord-Fasteners, of which the following is a specification.

My invention relates to cord fasteners for securing packages, and is more particularly adapted for use in the mail service, for tying together letters or other mail matter.

The primary object of my invention is the production of a simple, inexpensive and convenient cord-fastening device by means of which bundles of letters or other mail matter, or packages of any kind, can be quickly bound with cord and the cord secured in a most effectual manner, and where- 20 by the cord can be as readily untied.

Another object of my invention is the provision of a cord fastener having means to enable it to be suspended from a cord or wire so that a large number of fasteners 25 may at all times be retained in convenient position side by side on the cord and conveniently detached therefrom, either singly or in quantities as needed.

Another object of my invention is the provision of a cord fastener which can be as readily used by persons who habitually use their left hand rather than their right as by those using their right hand.

A further object of my invention is to so 35 construct the cord fastener that provision is made for readily changing the direction of the cord and retaining the latter in secure connection with the fastener.

Other objects are to construct a fastener 40 of this type of wire, the wire being bent, curved or otherwise fashioned to provide an attaching portion at one end, a supporting portion at its other end, and two direction-changing portions at the sides for changing 45 the direction of the cord in passing the same around a package or bundle, and securing the cord to the fastener, said direction-changing portions having each a cord securing portion by means of which the free end 50 of the cord is securely fastened; and to otherwise improve on cord fasteners of this type now in use.

To these ends the invention consists in the novel features of construction and in the arrangement of parts to be hereinafter

described and more particularly pointed out in the subjoined claims.

In the drawings, Figure 1 is a perspective view of a package of letters fastened together by means of a cord and my improved cord fastener. Figs. 2 and 3 are plan views of the package showing different steps in the act of connecting the cord to the fastener. Fig. 4 is a perspective view showing the manner in which cord fasteners 65 are suspended from a wire to permit of conveniently detaching them as needed.

Referring now to the drawings in detail, like numerals of reference refer to like parts in the several figures.

The reference numeral 5 designates a package of envelops or letters adapted to be tied together by means of a cord 6 and my improved cord fastener 7.

The cord fastener is constructed of wire 75 bent, curved, twisted or otherwise fashioned to provide at one end an attaching portion 8 to which one end of the cord 6 is attached, as at 9, at its other end a supporting portion 10 by means of which the fastener may be 80 suspended from a wire, as will be herein-after more particularly set forth; and two direction-changing portions 11 at opposite sides around which the cord is adapted to be wound for changing the direction of the 85 same, each direction-changing portion having a securing portion 12 in which the end of the cord is adapted to be secured.

The wire from which the fastener is constructed is bent at a point between its ends 90 in substantially heart-shape, as at 13, with an inwardly projecting U-shaped portion 14 slightly restricted in width at its outer end, as at 15. At the point or apex of the heart-shaped portion the wire is twisted, as at 16, 95 and the two stretches of wire directed laterally in opposite directions, as at 17, 18, the two stretches 17, 18 being recurved upon themselves, as at 19, 20, respectively, and these recurved portions being doubled upon 100 themselves, as at 21, 22, respectively, to provide the securing portions or cord clamping spaces 12. The two stretches of wire, at the points where they are doubled upon themselves, are recurved or directed inwardly to 105 meet each other, as at 25, and are thence twisted upon themselves, as at 26; the ends of the wire being fashioned to provide an attaching eye 27. The heart-shaped portion 23 serves as the supporting portion of 110

the fastener by means of which it may be suspended from a wire 28, as shown in Fig. 4, and by thus supporting the fasteners side by side they may be conveniently removed in the quantities needed by simply pulling upon the cord hanging therefrom. The restricted portion of the U-shaped part 14 of the heart portion serves to retain the fastener on the wire 28 and grip the wire sufficiently to necessitate a slight pull upon the cord 6 to remove the fastener from the supporting wire 28.

The eye 27 and the twisted portion 26 of the wire adjacent to said eye constitute the attaching portion of the fastener, while the portions 17, 19, and 21 and the portions 18, 20 and 22 form two lateral wings which serve as direction-changing portions for changing the direction of the cord in passing the same around a package or bundle and around the fastener to the securing portion of one of said wings. The spaces 12 between the portions 17 and 19 and the portions 20 and 22 of said lateral wings are gradually restricted inwardly so that in passing the end portion of the cord into either of said spaces, said cord will be wedged and retained and may be readily detached by grasping the end of the cord and pulling outwardly thereon toward the enlarged portion on said space.

Each of the two lateral wings may be said to comprise two U-shaped parts arranged in juxtaposition with a slight outwardly flaring space between said parts. These lateral wings are exact counterparts so that they may be used interchangeably to enable a person habitually using the left hand to tie a package or bundle as readily as one using the right hand.

When fastening a number of articles together or when tying a bundle, the cord fastener is placed on the bundle and held in position with the thumb of one hand, the thumb being preferably placed against the central portion of the fastener so as to bear against both lateral wings thereof. The cord is then passed around the package or bundle in one direction and placed beneath one of the lateral wings of the fastener, and for convenience in placing the cord under either of said lateral wings these wings are given a slight upward curve at their outer ends. After the cord is placed underneath one of the wings it is passed over the twisted portion 26 of the fastener and continued around the package or bundle at right angles to the portion previously passed around the

same. The end portion of the cord is then brought to a point in line with the opposite wing of the fastener and passed underneath the same, thence over the twisted portion 16 and underneath a portion of the first-mentioned wing, the end of the cord being thrust into the clamping space provided in 65 said first-mentioned wing and securely fastening the cord in position.

Having thus described my invention, what I claim is,—

1. A cord fastener formed of wire bent 70 or fashioned to provide a clamping portion at one end adapted to engage a cord or wire for suspending the fastener, a twisted portion at the inner end of said clamping portion, two laterally-disposed wings formed by 75 bending the wire outwardly in opposite directions from said twisted portion and recurring the same, thence doubling the wire upon itself at opposite sides and recurring the same to meet at a common point, the 80 wire where doubled upon itself being separated by slight spaces, said wire being twisted together at said common point and at the outer end of said twisted portion being formed into an attaching eye. 85

2. A cord fastener formed of wire bent between its ends to provide a heart-shaped portion having a U-shaped part extending inwardly from its large end, the wire being twisted together at the point or apex of the 90 heart-shaped portion and directed laterally and at opposite sides and fashioned at each side into two U-shaped parts constituting opposite wings, said U-shaped parts being separated by slight spaces, the wire at the 95 opposite ends of said wings being twisted upon itself and finally shaped into the form of an eye.

3. A cord fastener formed of a single piece of wire bent to provide an attaching 100 portion at one end, and opposite laterally extending portions provided with cord receiving spaces, said laterally extending portions being adapted to have a cord passed around the same to change the direction of 105 the cord and either of said cord receiving spaces being adapted to receive the end portion of the cord, as and for the purpose set forth.

In testimony whereof I affix my signature 110 in presence of two witnesses.

ALEXANDER J. MACKENZIE.
